UNITED STATES PATENT OFFICE.

CHARLES NICHOLS AND JAMES W. SPENCER, OF SEYMOUR, CONNECTICUT.

FOUNTAIN-PEN.

SPECIFICATION forming part of Letters Patent No. 726,561, dated April 28, 1903.

Application filed April 29, 1902. Serial No. 105,224. (No model.)

To all whom it may concern:

Be it known that we, CHARLES NICHOLS and JAMES W. SPENCER, citizens of the United States, residing at Seymour, county of New Haven, State of Connecticut, have invented 5 a new and useful Fountain-Pen, of which the following is a specification.

This invention relates to certain improvements in fountain-pens.

10 Fountain-pens as ordinarily constructed may be divided into two classes, which we will term, for convenience, "withdrawing" and "non-withdrawing" pens—that is, a class of pens in which when not in use the pen-carrier, 15 pen, and feed are withdrawn into the barrel, thereby greatly shortening the pen as a whole and rendering it very much more convenient for carrying about in the pocket, and a class of pens which we have termed "non-withdrawing" pens, in which the pen-carrier, pen, and feed do not withdraw into the barrel when not in use, and consequently the pen as a whole is considerably longer and less convenient to 20 carry about. Heretofore, so far as we are aware, in withdrawing-pens—that is, pens in 25 which the carrier and feed have longitudinal movement and may be withdrawn into the barrel when not in use—the construction has been such as to render a front shut-off—that 30 is, a shut-off in front of the pen—impracticable, so that it has been necessary to carry the pen with the carrier and feed upward, so as to prevent leakage, and the danger of leakage in transportation when filled has been a 35 serious objection to this class of pens.

It is one of the objects of this invention to provide a fountain-pen of the withdrawing type which shall be provided with an effective front shut-off, so that in carrying it about 40 in the pocket or in packing it for transportation when filled it is a matter of no consequence whatever in what position the pen may be placed.

A further object of the invention is to provide 45 a fountain-pen of the withdrawing type having a cap adapted to act as a screw-cap and shut-off when applied to the front end of the barrel and as a slide or a friction-cap when applied to the rear end or butt of the barrel 50 and used to project or withdraw the carrier, pen, and feed.

A further object of the invention is to pro-

vide a fountain-pen of the withdrawing type having an open-end spiral made independent of the carrier and a carrier adapted to receive any ordinary feed and any ordinary pen. The feed and pen may be easily taken out, if required, for cleaning or other purposes.

With these and other objects in view the invention consists in certain constructions and in certain parts, improvements, and combinations, which will be hereinafter described and then specifically pointed out in the claims hereunto appended.

In the accompanying drawings, forming part of this specification, in which like characters of reference indicate the same parts, Figure 1 is a longitudinal section, on a greatly-enlarged scale, of our novel pen in the closed position, the carrier, pen, feed, and spiral appearing in elevation; Fig. 2, a similar view showing our novel pen as in use, the carrier, pen, and feed being projected and the cap in position on the rear end of the barrel; Fig. 3, a section on the line 3 3 in Fig. 1; Fig. 4, a view of the slotted sleeve detached; and Fig. 5 is a detail sectional view of the carrier detached.

A denotes the barrel, which is ordinarily 80 made slightly tapering at both ends, and B the tip, which is secured thereto by a screw-thread 10.

C denotes the pen-carrier, D the pen, and E the feed. The carrier is provided with a 85 socket 11 to receive the feed and with a shoulder 12, against which the butt of the pen rests. Any ordinary style of feed and any ordinary style of pen may be used. The carrier is also provided with a shank 13, having a lug 14, 90 which is adapted to work in a slot or groove 15, formed in a hollow or tubular member 15', and also within the straight slot 16 in a sleeve 17, which fits closely in the barrel, so as not to turn therein. The spiral groove 15 and straight slot 16 are open at their forward ends, whereby the lug 14 may be readily inserted in or withdrawn from said groove and slot. The member 15' is provided with a shank 19. The barrel is ordinarily formed with a solid 100 head and then drilled to make a hole 20, through which shank 19 passes, then reamed to leave a shoulder 21, against which the base of the spiral rests, and then reamed again to

form a shoulder 22, against which the end of the sleeve rests. The object in providing shoulder 22 is to prevent sleeve 17 from being pushed to the extreme inner end of the 5 barrel and permit a hook to be inserted and passed over the inner end of the sleeve to withdraw it from the barrel, it being understood, of course, that this sleeve fits the normal inner diameter of the barrel, which comprises the ink-reservoir 23. Slot 16 in the sleeve does not ordinarily extend quite to the inner end thereof, so as to leave at the inner end a perfect ring, as at 24. In the rear end or butt of the barrel we form a recess 25 to 15 receive a suitable packing 26, as a cork, through which shank 19 passes and may turn therein, but which effectually prevents the escape of ink at that end of the pen. Outside of recess 25 is a shoulder 27 to receive a 20 corresponding hub on a head 28, which is rigidly secured to shank 19, as by a drive fit. Head 28 is shown as made slightly tapering to correspond with the general contour of the rear end of the barrel. It should be noted, 25 however, that at the point of contact of the head with the end of the barrel the head is of slightly-greater diameter than the end of the barrel, as at 29, to adapt it to be engaged with a frictional contact by the slightly-flaring open end 30 of the cap F, as in Fig. 2, so that the cap, head, and spiral may be rotated to project or withdraw the carrier, pen, and feed, as will be more fully explained. In the 30 closed position, as in Fig. 1, the flaring open end of the cap receives the barrel and engages the surface thereof freely at a distance from the front end. At the inner end of the cap is rigidly secured a plug 31, having a shoulder 32 of reduced diameter and a threaded portion 33 of still smaller diameter. This threaded portion is adapted to engage a corresponding internal thread at the outer end of the tip, and shoulder 32 forms a perfectly-tight connection with an accurately-beveled 35 incline 34 at the outer end of the tip, the external diameter of the tip being slightly greater than the diameter of the shoulder, so that the shoulder will pass within the open end. This is in order to avoid danger of leakage should the edge of the tip become slightly bruised or chipped.

The operation of our novel pen is briefly as follows: Suppose the pen to be in the closed position, as in Fig. 1. The operator removes 40 the cap by turning it backward, disengaging the threaded portion of the plug from the thread at the outer end of the tip. He then places the cap on the rear end of the pen, the open end of the cap engaging head 28 with a 45 frictional contact, so that by turning the cap forward the head and the spiral will be rotated and through the engagement of lug 14 on the shank of the carrier with the spiral and also with the straight slot in sleeve 17, as clearly shown in both Figs. 1 and 2, the carrier and with it the pen and feed, will be 50 propelled from the position shown in Fig. 1

to the operative position, as in Fig. 2, it being of course immaterial whether or not the cap is detached from head 28 while the pen is in use. When through using the pen the operator turns the cap, as in Fig. 2, and with its head 28 and the spiral, backward and through the engagement of lug 14 with the spiral and the straight slot withdraws the pen from the operative position, as in Fig. 2, into the barrel, as in Fig. 1, the operator then removes the cap from head 28, places it over the front end of the barrel, and turns the threaded portion of the plug into engagement with the internal thread in the end of the tip until shoulder 31 is placed closely in engagement with incline 34 at the end of the tip, as in Fig. 1, thus forming an effectual front shut-off for the ink, so that the pen may be placed in any position without danger of leakage.

Having thus described our invention, we claim—

1. A fountain-pen comprising a barrel, a stationary sleeve inclosed therein and provided with a straight slot or groove, a hollow member located within said sleeve and provided with a spiral slot or groove, and a pen-carrier having a shank provided with a lug working in both said straight and spiral slots or grooves, said slots or grooves being open at their forward terminals, whereby said lug may be withdrawn therefrom.

2. A fountain-pen comprising a barrel, a stationary sleeve inclosed therein and provided with a straight slot or groove, a hollow member located within said sleeve and provided with a spiral slot or groove, a shank extending from said hollow member, a head carried by said shank, and a pen-carrier having a shank provided with a lug working in both said straight and spiral slots or grooves, said slots or grooves being open at their forward terminals, whereby said lug may be withdrawn therefrom.

3. A pen-carrier comprising a tubular body forming a socket for the feed and provided with a shoulder.

4. A pen-carrier comprising a tubular body forming a socket for the feed and provided with a shoulder, and a shank extending from said tubular body.

5. A tubular member provided with a spiral groove or slot arranged to guide the shank of a pen, and a shank extending from said member, said groove or slot being open at its forward end to permit of the withdrawal of said pen-shank.

6. In a fountain-pen the combination with a tip having an incline and an internal thread, of a cap having at its inner end a plug provided with a shoulder adapted to engage the incline and a screw-thread adapted to engage the internal thread on the tip, whereby a cut-off is made at the end of the tip.

7. In a fountain-pen the combination with a barrel, a tip having an incline and an internal thread, a pen-carrier and means for pro-

propelling and withdrawing the carrier, of a head at the base of the barrel for operating the propelling means, said head being slightly tapering and of slightly greater diameter than the barrel at the point of contact and a slightly flaring cap adapted to engage the head and having at its inner end a plug with a shoulder adapted to engage the incline, and a screw-thread adapted to engage the internal thread on the tip.

8. In a fountain-pen the combination with the barrel having a hole or opening therein and two concentric shoulders, a sleeve having a straight slot or groove located within said barrel and bearing against one of said shoulders, a hollow member located within said sleeve and having an open-ended spiral slot or groove formed therein, said member projecting beyond the inner end of said sleeve and bearing against the second shoulder of the barrel, a shank formed with said hollow member and projecting through said hole or opening, and a pen-carrier having a shank provided with a lug working in both said straight and said spiral grooves or slots.

9. In a fountain-pen the combination with a barrel having a hole 20, a recess 25 and a shoulder 27, a pen-carrier, a hollow open-ended spiral having a shank passing through hole 20, and operating connections interme-

diate said spiral and the pen-carrier, of packing in said recess through which the shank passes and a head 28 secured to the shank and having a hub-engaging shoulder 27.

10. A fountain-pen comprising a barrel, a stationary sleeve inclosed therein and provided with a straight slot or groove, a hollow member located within said sleeve and provided with a spiral slot or groove, and a pen-carrier having a lug working in both said straight and spiral slots or grooves, said slots or grooves being closed at their inner terminals to limit the inward movement of said lug, and open at their outer terminals, whereby said lugs may be withdrawn therefrom.

11. In a fountain-pen the combination with a barrel, a tip having an internal incline and a thread and a pen-carrier, of means for propelling and withdrawing the carrier and a cap having a plug with a shoulder adapted to engage the incline and a screw-thread adapted to engage the thread on the tip.

In testimony whereof we affix our signatures in presence of two witnesses.
